UNITED STATES PATENT OFFICE.

GEORGE C. THOMPSON, OF EAST LIVERPOOL, OHIO, ASSIGNOR TO THE C. C. THOMPSON POTTERY CO., OF EAST LIVERPOOL, OHIO.

DESIGN FOR A DISH OR ANALOGOUS ARTICLE.

Application filed May 6, 1926. Serial No. 17,587. Term of patent 7 years.

To all whom it may concern:

Be it known that I, GEORGE C. THOMPSON, a citizen of the United States, residing at East Liverpool, in the county of Columbiana and State of Ohio, have invented a new, original, and ornamental Design for a Dish or Analogous Article, of which the following is a specification, reference being had therein to the accompanying drawings.

The predominant feature of the design is the plurality of flat side wall surfaces arranged at angles, to one another and stopping short of the upper edge of the dish.

In the drawings:

Figure 1 is a top plan view of the article showing my new design.

Figure 2 is a side view thereof.

I claim:

The ornamental design for a dish or analogous article, as shown and described.

In testimony whereof, I hereunto affix my signature.

GEORGE C. THOMPSON.
